(57) **CLAIM**

The ornamental design for a go cart, as shown and described.

DESCRIPTION

FIG. 1 is a front view of the go cart in accordance with my new design;

FIG. 2 is a rear view thereof;

FIG. 3 is a left side elevational view thereof;

FIG. 4 is a right side elevational view thereof wherein the pedal components are moved to an alternate position;

FIG. 5 is a top plan view thereof;

FIG. 6 is a front perspective view thereof; and,

FIG. 7 is a rear perspective view thereof.

All broken lines shown in the FIGS illustrate portions of the go cart that form no part of the illustrated design.
